UNITED STATES PATENT OFFICE.

ALFRED COTTON, OF NEWARK, NEW JERSEY.

AUTOMATIC STOKER.

1,167,982.

Specification of Letters Patent. Patented Jan. 11, 1916.

Application filed May 4, 1910. Serial No. 559,287.

To all whom it may concern:

Be it known that I, ALFRED COTTON, a subject of the King of Great Britain, and resident of the city of Newark, county of 5 Essex, and State of New Jersey, have invented certain new and useful Improvements in Automatic Stokers, of which the following is a specification, reference being had therein to the accompanying drawings, 10 in which—

Figure 1 is a front elevation of the stoker and a portion of the front of the furnace; Fig. 2 a side elevation, the furnace front being shown in vertical sectional view; Fig. 15 3 a central vertical sectional view substantially on the line III—III of Fig. 1; Fig. 4 a plan view with the fuel hopper removed; Fig. 5 a horizontal sectional view substantially on the line V—V of Fig. 1; Fig. 6 a 20 similar view through the shovel compartments, substantially on the line VI—VI of Fig. 1; Fig. 7 a horizontal sectional view of the furnace showing diagrammatically the throw of the fuel by the shovels; and Fig. 25 8 a detail vertical sectional view showing the means for operating the fuel gates. Fig. 9 a detail sectional view of the diaphragm clutch controlling chamber.

This invention relates to improvements in 30 that class of automatic stokers in which small portions of fuel are successively delivered over the fire to progressively cover the fire with fresh fuel, each successive throw of the shovel, or fuel delivering device, depositing the fuel over a different portion of the grate.

One of the objects of the invention is to provide such a stoker with a horizontally-swinging fuel delivery device whereby the 40 fuel will be delivered in a layer of uniform thickness over the grate and the device will distribute the fuel over a grate of considerable width. I have found that vertically-swinging fuel delivering devices do not 45 properly distribute fuel over grates of any considerable width. I have also found that with my horizontally swinging fuel delivering device I am able to readily cover grates of extreme width and of any desired length 50 or depth.

Another object of the invention is to provide means whereby the horizontally-swinging shovels will be automatically adjusted as to the speed and strength of their movements and as to the arc through which they move, in order to secure an even distribution

of the fuel and to prevent the fuel being thrown against the side walls of the fire box, particularly when throwing the fuel the extreme depth of the grate.

Another object of the invention is to provide a pair of horizontally moving shovels and means to operate said shovels alternately, each shovel being arranged to deliver fuel over one half of the grate.

A further object of the invention is to provide means whereby the stoker will be automatically stopped and started by the draft apparatus, the purpose being to have the stoker operating when the draft is on and to stop the stoker when the draft is shut off.

Other important objects and advantages of the invention will be pointed out hereinafter.

Referring to the various parts by numerals, 1 designates the boiler; 2 the smoke box door which gives access to the boiler tubes; 3 the fire brick lining; 4 the dead plate; 5 the grate bars; 6 the fire door and 7 its baffle plate.

8 designates the usual furnace front which carries the stoker mechanism and 9 and 10 are baffle plates which aid in protecting the furnace front from the heat of the fire. These plates may be provided with perforations 11 to admit of circulation of air to keep them cool and to admit air over the grate to improve combustion.

The stoker mechanism is carried by three horizontal plates, the bottom plate 12, the intermediate or middle plate 13 and the top plate 14. The boiler front is provided with a stoking aperture 15 on the lower wall of which rests the forward edge of the bottom plate 12 and on the upper wall of which bears the inner end of the top of the middle plate 13. The bottom plate is provided with a depending flange which contacts with the face of the boiler front and prevents any forward movement of the bottom plate 100 through the stoking aperture.

The fuel distributing shovels are carried by shovel arms 17 which are mounted on vertical pivots 18 extending between the bottom plate and the intermediate plate, said pivots projecting upwardly through the intermediate plate, for a purpose which will be hereinafter described.

The bottom plate is provided with upwardly extending walls 19 and 20, said walls being arranged on arcs struck from the centers of the shovel pivots 18, said concentric

walls forming curved channels or races in which the shovels oscillate. The walls 19 intersect at the center lines of the stoker and terminate at a point some distance in 5 the rear of the stoking aperture in the furnace wall; and the walls 20 terminate at their inner ends at the sides of the stoking aperture in a vertical plane with the front wall of the furnace, as shown clearly in 10 Fig. 6. The shovels swing in the curved races thus formed and deliver the fuel over the grate with a horizontal movement. The centers of the shovel pivots are directly in the rear of the side walls of the stoking 15 aperture. The shovel-carrying arms 17 are secured to the tops of the shovels and extend forwardly over the shovel to form a guard 21 which prevents the fuel rising above the shovel during the throwing operation. The curved walls 19 extend to the intermediate plate 13 and from a close joint therewith, while the plates 20 terminate short of the middle plate to leave horizontal openings through which the shovel arms 20 swing. The bottom plate is also formed with upwardly projecting walls 22, said walls being parallel and extending rearwardly from the side walls of the stoking aperture and having openings 23 therein 25 through which extend the outwardly projecting lever extensions 24 of the shovel arm.

The rear edges of the bottom plate and the middle plate are connected together by 30 vertical plates 25 which are connected at their outer edges to the rear edges of the wall 22 and at their inner edges to the rear edges of the walls 20. The rear ends of the shovel races are closed by gates 26 35 which are pivoted on bolts 27 extending horizontally across the upper portion of the races, the ends of said bolts being secured to the rear ends of the walls 19 and to the inner ends of the plates 25. These gates are 40 provided with flanges at their lower ends which fit over the rear edge of the bottom plate and thereby close the rear ends of the shovel races. The plates 25 are secured in position by bolts 25^a so that they may be 45 readily removed together with the gates 26 and thereby permit of the removal of the shovels.

The plates 12, 13 and 14 are connected together by vertical bolts 28 and the top plate 50 is bolted to the boiler front by bolts 29 which pass through outwardly extending lugs 30 formed at the upper edge of said plate, as shown clearly in Fig. 1.

The top plate is provided at its inner corners with the depending angular flanges or extensions 31, one member of said flange fitting closely against the furnace front, the other member thereof being parallel with the side edge of the plate. These flanges extend 55 slightly below the bottom plate as

shown clearly in Figs. 5 and 6 and inclose the bolts 28. To the side members of these flanges are secured brackets 32 to each of which is pivoted the rearwardly and outwardly extending lever 33 each of said levers carrying at its outer end an adjustable eye-bolt 34 at the outer end of which is connected a shovel actuating spring 35, the inner end of said spring being connected to the outer end of the lever extension 24. By 70 adjusting the bolt 34 the proper initial tension of the spring 35 may be obtained.

Pivoted on a central vertical shaft 36 mounted in suitable bearings near the rear edge of the plates 12 and 13 is a double armed horizontal lever 37. This lever extends rearwardly from the shaft 36 and connected to each arm thereof is a link 38, the other ends of said links being connected to the adjoining spring extending lever 33, 80 whereby said levers and the double armed lever 37 will move in unison and in the same direction. Shaft 36 extends through the intermediate plate 13 and is journaled in a bearing 39 formed on the under side of a cross 90 bar 40 of the top plate, which will be herein-after more fully described. Secured rigidly to the shaft 36 above plate 13 is a double-armed lever 41, said arms normally lying parallel with the front wall of the furnace. 95 Loosely pivoted on the shaft 36 below the lever 41 is a claw like cam 42 having the arms 43, said cam being in general shape like a pair of external calipers with its arms somewhat extended. On the upper surface 100 of said cam equal distances from the center line thereof are formed threaded lugs 44 in which are screwed adjustable contact rods 45, the inner ends of said rods being in such position that they may be brought into contact with the forward faces of the arms of the lever 41 as the cam 42 is rocked on its pivot. By adjusting the contact rods the time of contact between said rods and the arms 41 may be properly arranged and the 105 amount of movement which it is desired to give the shaft 36 may be secured. Connected to the cam 42 at a point midway between its ends and at a suitable distance radially from the center of its pivot is an 110 operating pitman 46, the other end of said pitman being connected to a suitable reciprocating means, as will be more fully herein-after described. It will, therefore, be seen that by vibrating the cam 42 the required 115 amount of motion will be communicated to the shaft 36 and through the lever 37 and links 38 to the spring extending levers 33.

The pivots 18 of the shovels extend above the intermediate plate and on each of said pivots above said plate is rigidly secured a two-armed shovel latch 47, one of said arms 48 constituting a latch arm and the other arm 49 constituting a setting arm. On the plate 13 adjacent each pivot is mounted a 120 125 130

shovel locking lever 50 having a locking arm 51 and a trip arm 52. The locking arm 51 is provided with a shoulder which is adapted to be engaged by the end of the latch arm 48 of the shovel latch when the shovel is in its rearward position and to hold said shovel in said position against the tension of the actuating spring 35.

The ends of the arms 43 of the claw cam 10 are bifurcated horizontally and the arms 49 of the shovel latches are adapted to rock in between the members 43^a on the bifurcated portion of the arms 43. Between said portions 43^a is secured a latch setting roller 53. 15 The arm 52 of the locking lever overlies the bifurcated portion of the cam arms 43. On the upper surface of each arm 43 is formed a threaded lug 54 in which is mounted an adjustable trip 55. The trips 55 are so located that when the claw cam 42 has nearly completed its movement in one direction the trip 55 will contact with the arms 52 of the locking lever 50 and move said lever sufficiently to release the shovel latch 47. The 25 setting roller 53 of the outwardly moving arm of the cam 42 will engage the arm 49 of the shovel latch, thereby swinging the attached shovel rearwardly and causing the latch arm 48 to be engaged by the locking 30 arm 51 of the locking lever. An arm 56 is connected to each locking lever and to this arm is connected a spring 57, said spring tending to throw the locking lever arm 51 inwardly or toward the shovel latch 47 and 35 holding said lever in engagement with the shovel latch until the trip device 55 swings the locking arm on its pivot as previously described. On the plate 13 is arranged a stop 58 against which the arm 56 rests after 40 the shovel latch is released from the locking lever. By this means the locking lever is held in position to be properly engaged by the shovel latch.

From the foregoing it will be noted that 45 the shovels are operated alternately. It will also be noted that both shovels are withdrawn at the time of the release of one shovel, that is to say, one shovel is just completing its rearward movement when the 50 other shovel is released to make its forward or throwing movement. This is important as will be more fully hereinafter set forth.

In order to progressively vary the throw 55 of the shovels and thereby progressively cover the grate with fuel means are provided for gradually varying the tension of the springs 35. This means, as shown in the drawing, consists of an approximately heart-shaped cam 59 mounted on a vertical shaft 60 which carries near its lower end a worm gear 61, said gear being driven by a worm 62. A bar 63 provided with rollers 64 engaging opposite sides of the cam is connected to the adjusting lever 33. The cam 59 is 65 formed approximately as shown, in order

that there will be a uniform rate of movement of the bar 63 throughout the rotation of the cam 59. The bar 63 carries the perforated lug 65 which slides on the guide pin 66 to secure the proper reciprocating motion 70 of the bar 63. It will thus be seen that during the rotation of the cam 59 the levers 33 will be swung on their pivots, one of said levers being moved outwardly and in an arc bringing the end of the bolt 34 closer to the 75 pivot 18 of the shovel and closer to the point of attachment between the inner end of the actuating spring 35 and the extension of the shovel arm. It will also be noted that the center line of the spring will be varied with 80 respect to the longitudinal center line of the stoker and also becoming more and more acutely inclined toward said center line as the tension of the spring 35 is released and becoming more and more obtusely inclined 85 and nearer a perpendicular of the center line as the tension on said springs is increased. It will, of course, be understood that the release point of the shovel is approximately 90 on a line drawn from the point of attachment between the spring and the arm 34 and the pivot of the shovel after the shovel has completed its fuel throwing movement. It will, therefore, be seen that the released position of the shovel will be varied to correspond with the varying position of the spring extending arm 33. It will also be understood that the variation of the released position of the shovel will result in the variation of the throw of the shovel. This variation is clearly illustrated in Figs. 6 and 7 of the drawings. It will be noted that when the spring 35 is at its lowest tension, the released position of the shovel is such that the fuel thrown by the shovel will be distributed laterally over the greatest distance. This results from the fact that the shovel 100 will travel through its greatest arc of movement when the spring is at its lowest tension. As the tension of the spring is increased the arc of movement, or the length of travel, of the shovel is restricted for the reason that the line between the center of the shovel pivot and the point of attachment of the actuating spring to the spring extending lever is moving nearer to a perpendicular position with respect to the longitudinal center line of the furnace. As the tension of the spring is decreased the arc of movement, or length of travel, of the shovel is increased for the reason that the point of attachment of the actuating spring to the spring extending lever is moving toward the longitudinal center line of the furnace, thereby increasing 110 the distance through which the arm 24 must pass before it reaches a point directly in line between the shovel pivot and the point of attachment of said spring to said lever. It is manifest that as the spring extending lever 115 moves outwardly the distance through which 120

125 130

the arm 24 must pass before it comes to rest becomes gradually less and less. The result is that the arc of movement of the shovel grows gradually less and less until the minimum is reached at the greatest extension of the actuating spring. It will, of course, be understood that the spring connected to one shovel is gradually extended and that the other spring is at the same time permitted to gradually contract, and that the greatest tension on one spring is reached at the time of the greatest contraction of the other spring. It will also be understood that the springs will be gradually extended to increase their tension and will be then gradually released to lower their tension, and that when one spring tension is being increased the other spring tension is being reduced.

By reference to Fig. 7 of the drawings it will be noted that when the shovels are working under their highest tension the angle of throw of the shovel will be the lowest so that the lateral spread of the fuel will be considerably less than when the shovel is working under its lowest tension. This is desirable. If the arc through which the shovel moves in its throwing movement were not reduced for the high tension movements a great deal of fuel would be thrown against the side wall of the fire box. It will be seen that this would be a very undesirable condition and it is to avoid this that the arc of movement is reduced as the tension of the actuating spring is increased. By this means the lateral distribution of the coal is maintained uniform while the distant or forward throw of the shovel is increased. This is a very important feature in the operation of horizontally swinging shovels.

The link 46 is connected to a crank disk 67 secured to the upper end of a vertical shaft 68 mounted in the bracket 69, said bracket being suitably bolted to the boiler front. The shaft 68 carries a worm gear 70 rotated by means of a worm 71 carried by the driving shaft 72. By this means the claw cam 42 is oscillated for the purpose of operating the shovel setting and shovel releasing devices. The driving shaft is formed with a cone pulley 73 which runs loosely on the shaft and is formed with a clutch member 74. Slidable on the shaft and rotating therewith is a clutch member 75 operated by means of the pivoted lever 76. This lever is provided with a perforated lug 77 to receive a pin 78 to lock the clutch out of engagement and the apparatus out of operation. The lever 76 is provided with a dog 79 which is adapted to lie close to the periphery of the cam disk 67 when the clutch members are in engagement. The crank disk is provided with diametrically opposite notches 80, said notches being so formed that they will be in a position to re-

ceive the dog 79 when both shovels are retracted or in their rearward positions, as previously described. By this means it will be impossible to stop the stoker by releasing the clutch when either of the shovels is in its forward position and therefore exposed to the fire. To provide means for automatically stopping the stoker in response to the draft the clutch lever is extended as at 81 and is provided with a plunger head 82. This head is engaged to bear on a diaphragm 83 forming one wall of a pressure chamber 84. This chamber is connected by a pipe 85 with the steam supply pipe 86 leading to the ash pit blower or other suitable draft apparatus. A spring 87 is provided to keep the plunger against the diaphragm and to hold the two members of the clutch disengaged. It will be readily understood that when the blower is in operation the pressure in chamber 84 will be such as to hold the clutch members in engagement; and that when the pressure in the chamber 84 is reduced by reason of shutting down the draft the spring 87 will force the plunger inwardly against the diaphragm and release the clutch members, thereby stopping the stoker apparatus. On the lower end of shaft 68 is a beveled gear 88 which meshes with a similar gear 89 on shaft 90, said shaft 90 carrying worm 62 by means of which shaft 60 is operated.

The top plate 14 is formed with a fuel receiving opening 91 near its inner edge, said opening being formed by a slightly raised face on which rests the lower edge of the fuel hopper 92. The rear side of the fuel hopper is supported by the cross bar 40. On the shaft 36 is mounted the fuel feeding ram 93, said ram resting on the upper surface of the bottom 94 of the fuel chamber, said bottom being formed integral with the upper plate 14 and being spaced intermediate the top plate and the middle plate 13. As the shaft 36 is oscillated the ram feeds fuel first to one shovel and then to the other, as will be more fully hereinafter described. The ram is semi-circular in plan view, its forward edge being parallel with the boiler front. Forward of the ram the fuel chamber is divided centrally by a vertical partition 95 and each pocket or portion of the fuel chamber is formed with the forwardly and downwardly inclined portion 96 which leads to an opening 97 in the intermediate plate 13, said opening being just forward of the rearward position of the shovel, whereby the fuel fed by the ram will fall through the opening 97 directly in front of the shovel when the shovel is in position to be released for its forward throwing movement.

To prevent the fuel falling behind the shovel, and to hold it in the fuel chamber until the shovel has reached its rearward position, timing gates 98 are pivoted on supports 99 mounted in the fuel chamber for

ward of the partition 95. The pivots of these gates will extend outwardly through the side wall of the fuel chamber and are provided on their outer ends with an upwardly extending crank arm 100. Connected to this crank arm is a spring pressed rod 101 which projects outwardly through the strengthening rib 102 of the top plate and on the outer end of this rod is secured a 10 depending finger 103. On the end of each of the arms 43 of the claw cam 42 is an upwardly extending finger 104 which is adapted to engage the finger 103 when the arm 43 has very nearly reached the limit of 15 its rearward movement and the shovel positioned by said arm has reached its rearward latched position. When the finger 103 is moved rearwardly the timing gate will be swung forwardly permitting the charge of 20 fuel to drop through the opening in plate 13 in front of the shovel in the shovel race. As soon as the fingers 103 and 104 are disengaged the spring pressed rod will return the timing gate to its normal closed position. 25 The fuel hopper is provided on its rearward side with pivot lugs 105 which correspond with similar lugs on the top plate 14 and to which they are pivoted. Said hopper is also provided on its forward side with 30 similar pivot lugs which are adapted to be connected to lugs on a latch plate 106, said latch plate being adapted to fit within the opening 107 of the top plate and to form a cover for the fuel chamber forward of the 35 fuel hopper. The latch plate is provided at its rear edge with a latch 108 which is adapted to engage under the cross-bar 40 and to hold the hopper in place until the latch plate is raised. 40 The front wall of the fuel chamber is provided with a door 109 through which access may be had to the interior of the ram compartment.

Having thus described my invention, what 45 I claim as new and desire to secure by Letters Patent is:—

1. An automatic stoker comprising a horizontally swinging shovel, a tension means for moving said shovel through its fuel-throwing movement, and means for varying the tension on the shovel for successive throws to vary the velocity of the shovel movement and the longitudinal distribution of the fuel, said means also varying the inner limit of the shovel movement to vary the lateral or sidewise distribution of the fuel. 50

2. An automatic stoker comprising a horizontally swinging shovel, a tension means for moving said shovel through its fuel-throwing movement, and means for varying the inner limit of the shovel movement to vary the extent of the lateral distribution of the fuel. 60

3. An automatic stoker comprising a horizontally swinging shovel, a tension means

for moving said shovel through its fuel-throwing movement, and means for automatically varying the tension on the shovel for successive throws to vary the velocity of the shovel movement and the longitudinal distribution of the fuel, said means also varying the inner limit of the shovel movement to vary the lateral or sidewise distribution of the fuel. 70

4. An automatic stoker comprising a horizontally swinging shovel, a tension means for moving said shovel through its fuel-throwing movement, means for withdrawing the said shovel to the same point for each movement, and means for varying the inner 80 limit of travel of the shovel to vary the lateral distribution of the fuel. 75

5. An automatic stoker comprising a horizontally swinging shovel, a tension means for moving said shovel through its fuel-throwing movement, means for withdrawing said shovel to the same point for each movement, means for varying the tension on the shovel for each movement, said means also varying the inner limit of the travel of the 90 shovel in each successive movement to vary the lateral and longitudinal distribution of the fuel. 85

6. An automatic stoker comprising a horizontally swinging shovel, a tension 95 means for said shovel, means for automatically and progressively varying said tension means for successive shovel movements, said means also progressively varying the released or stopping position of said 100 shovel and thereby varying the length of travel of the shovel in successive fuel-throwing movements, means for withdrawing the shovel to the same rearward position for each movement, the tension varying means operating to shorten the travel of the shovel when increasing the tension and to lengthen the travel of the shovel when reducing the tension. 105

7. An automatic stoker comprising a 110 movable shovel, a tension means to move said shovel through its fuel-throwing movement, means for automatically varying said tension means for successive shovel movements, said means also varying the length 115 of the travel of the shovel in its fuel-throwing movement, said tension varying means operating to increase the tension while reducing the travel of the shovel and reducing the tension when increasing the travel of the 120 shovel. 120

8. An automatic stoker comprising a movable shovel, a tension means to move said shovel through its fuel-throwing movement, means for automatically varying said 125 tension means for successive shovel movements, said means also varying the inner limit of the travel of the shovel in its fuel-throwing movement, said tension varying means operating to increase the tension 130

while reducing the travel of the shovel and reducing the tension when increasing the travel of the shovel, and means for withdrawing the shovel to the same rearward 5 position for each movement.

9. An automatic stoker comprising a pivoted shovel, a coil spring for moving said shovel through its fuel throwing movement, means for withdrawing the shovel in opposition to the spring, means for locking it in its rearward position, means for automatically extending the spring to increase its tension for successive shovel movements, said means so varying the position of the 10 spring with respect to the shovel pivot as to vary the inner limit of the shovel movement, thereby varying the distance through which the shovel travels in successive fuel throwing movements.

20 10. An automatic stoker comprising a horizontally swinging shovel carrying an arm, a coil spring connected to said arm and serving to swing the shovel through its fuel throwing movements, means for withdrawing the shovel in opposition to said 25 spring, means for automatically increasing the tension of the spring and for swinging it so as to change its radial position with respect to the shovel pivot, whereby the distance through which the shovel will be 30 moved and the inner limit of the shovel movement is varied for each movement.

11. An automatic stoker comprising a pair of horizontally swinging shovels mounted 35 near the side edges of the stoking opening and extending toward each other in the same horizontal plane, a tension means for each of said shovels, means for moving each of said shovels in opposition to its tension 40 means, means for releasing said shovel for its fuel-throwing movement, means for automatically varying the tension to vary the throw of the shovel, said means also varying the inner limit of the shovel movement 45 and thereby varying the distance through which each shovel travels during its fuel-throwing movement.

12. An automatic stoker comprising a pair of horizontally swinging shovels extending 50 toward each other and each being arranged to deliver fuel to one half of the furnace grate, a coil spring connected to each of said shovels and arranged radially with respect to the shovel pivot, means for automatically 55 and progressively varying the tension of said spring on said shovel and varying its radial position with respect to the pivot of the shovel, means for moving the shovel rearwardly in opposition to the spring, and 60 means for releasing the shovel to permit the spring to move it through its fuel throwing movement, whereby the strength of successive shovel movements and the inner limit of the shovel movement will be varied.

65 13. An automatic stoker comprising a pair

of horizontally swinging shovels, curved shovel races for said shovels, radial arms connected to said shovels at their pivots, coil springs connected to said arms, spring extending levers connected to said springs and means for automatically swinging said levers in opposite directions, whereby one shovel spring will be extended while the other one is being distended whereby the tension of one of said springs will be increased and the other decreased during successive shovel movements. 70

14. An automatic stoker comprising a pair of horizontally swinging shovels, curved shovel races for said shovels, radial arms connected to said shovels at their pivots, coil springs connected to said arms, spring extending levers connected to said springs, means for automatically swinging said levers in opposite directions, whereby one shovel spring will be extended while the other one is being distended whereby the tension of one of said springs will be increased and the other decreased during successive shovel movements, and the radial positions of the springs with respect to the shovel pivots will be varied for each successive shovel movement to thereby vary the distance through which the shovel travels during each throw. 80

15. An automatic stoker comprising a pair of horizontally swinging shovels, an arm connected to each shovel at the pivot thereof, a coil spring connected to each of said arm and radially arranged with respect to the shovel pivot, a spring extending lever connected to each of said springs, means connecting said levers together whereby they will move in unison, and means for automatically moving said levers a uniform distance for each fuel throwing movement, the parts being so arranged that the tension of one spring will be increased and the tension of the other decreased during a series of shovel movements and the radial position of each spring with respect to the attached shovel will be uniformly varied throughout the variations in the spring tension. 90

16. An automatic stoker comprising a pair of horizontally swinging shovels, an arm connected to each shovel at the pivot thereof, a coil spring connected to each of said arms and radially arranged with respect to the shovel pivot, a spring extending lever connected to each of said springs, means connecting said levers together whereby they will move in unison, and means for automatically moving said levers a uniform distance for each fuel throwing movement whereby the tension of one spring will be increased and the tension of the other decreased during a series of shovel movements and the radial position of each spring with respect to the attached shovel will be uniformly varied throughout the variations in 110 115 120 125 130

the spring tension, means for withdrawing one shovel in opposition to its tension means and releasing the other shovel to permit it to make its fuel throwing movement.

17. An automatic stoker comprising a pair of horizontally swinging shovels, a tension means connected to each of said shovels and arranged to move it through its fuel throwing motion, a rocking shovel actuating cam, means whereby said cam will withdraw each shovel in opposition to its tension means, means for locking each shovel in its rearward position, means carried by the shovel actuating cam to release the shovel locking means, means for operating the shovel actuating cam whereby said cam will alternately set and release the shovels.

18. An automatic stoker comprising a pair of horizontally swinging shovels pivoted near opposite sides of the stoking aperture, a spring connected to each of said shovels and arranged to move the shovel through its fuel throwing movement, a spring extending lever connected to each of said springs, means connecting said levers together, means for moving said levers to alternately increase the tension of one spring and decrease the tension of the other spring, a rocking shovel actuating cam mounted between the shovels, means for rocking said cam, means carried by said cam to alternately withdraw the shovels against the spring tension, and means carried by said cam to alternately release the shovels.

19. An automatic stoker comprising a pair of horizontally swinging shovels pivoted near opposite ends of the stoking aperture, a tension spring connected to each of said shovels and extending radially with respect to the pivot thereof, a spring extending lever connected to each of said springs, means for swinging said levers to alternately increase and decrease the tension of said springs and to change their radial relation to the shovel pivots whereby the released position of the shovels will be varied and the tension of the springs on the shovels will be varied in succeeding movements, a rocking shovel actuating cam mounted between the shovels, means for rocking said cam, means carried by said cam to alternately withdraw the shovels, and means carried by said cam for alternately releasing the shovels.

20. An automatic stoker comprising a pair of horizontally swinging shovels mounted near opposite sides of the shovel stoking aperture and extending toward each other in the same horizontal plane, curved shovel races for receiving said shovels, means for alternately withdrawing and releasing said shovels, means for alternately delivering fuel in front of the withdrawing shovel, and a tension means for moving the shovel through its fuel throwing movement when said shovel is released.

21. An automatic stoker comprising a pair of horizontally swinging shovels arranged in the same horizontal plane and extending toward each other from their pivots, a curved race for each of said shovels, a tension means for each of said shovels, means for alternately withdrawing each shovel against its tension means, means for locking the shovel in its withdrawn position, means for delivering coal in front of each locked shovel, and means for alternately releasing the shovels to permit them to move forward under the influence of the tension means.

22. An automatic stoker comprising a pair of horizontally swinging shovels extending toward each other from their points of support, a tension means connected to each shovel to move said shovel through its fuel throwing movement, a locking cam connected to the pivot of each shovel, a pivoted latching lever, means for alternately moving the shovel locking cams to swing the shovel rearwardly and to cause the locking cam to engage the latching lever, and means for alternately releasing the latching lever to permit the released shovel to be moved by its tension means.

23. An automatic stoker comprising a pair of horizontally swinging shovels, a tension means for each of said shovels, a horizontally rocking shovel actuating cam mounted between said shovels, means connected to each of the shovels and adapted to be engaged by the shovel actuating cam to swing the shovels rearwardly, means for latching each shovel and means carried by the shovel actuating cam to release the latch devices.

24. An automatic stoker comprising a pair of horizontally swinging shovels, a tension means for each of said shovels, a horizontally rocking shovel actuating cam mounted between said shovels, means connected to each of the shovels and adapted to be engaged by the shovel actuating cam to swing the shovels rearwardly, means for latching each shovel, means carried by the shovel actuating cam to release the latch devices, and means for automatically varying the tension means whereby successive throws of the shovels will be varied.

25. An automatic stoker comprising a pair of horizontally swinging shovels, a tension means for each of said shovels, means for alternately setting and releasing said shovels and for alternately increasing the tension of one of the shovel tension means and decreasing the tension of the other shovel tension means.

26. An automatic stoker comprising a horizontally swinging shovel, a tension means for said shovel, and means for automatically varying the tension of the shovel tension means and varying the inner limit of the shovel movement thereby varying the distance through which the

- shovel travels in its fuel throwing movement.
27. An automatic stoker comprising a horizontally swinging shovel, a tension means for said shovel, means for moving said shovel against the tension means and for releasing it, and means for varying the tension of the shovel tension means and for moving said tension means to vary the inner limit of the arc of travel of the shovel.
28. An automatic stoker comprising a pair of horizontally swinging shovels, a shovel actuating cam mounted between said shovels, means for rocking said cam, means operated by said cam for alternately setting and releasing each of the shovels, a ram compartment above the shovels, a horizontal rotary oscillating ram in said ram compartment, and means whereby the shovel actuating cam will actuate the ram.
29. An automatic stoker comprising a pair of horizontally swinging shovels extending toward each other, an actuating spring connected to each of said shovels, a spring extending levers connected to said springs, a vertical ram shaft located between the shovels and in the rear thereof, a lever loosely mounted on said shaft, links connecting said lever to the spring extending levers, a shovel actuating cam, means for rocking said cam, means operated by said cam to alternately set and release the shovels, means carried by said cam adapted to rock the ram shaft, a ram compartment, and a horizontal ram in said compartment and rigidly connected to the ram shaft.
30. An automatic stoker comprising a horizontally swinging shovel, a shovel actuating cam, means operated by said cam to set and release the shovel, a tension means for said shovel to move it through its fuel throwing movement, a fuel feeding ram, a fuel gate between the ram and the shovel, and means operated by the shovel actuating cam to withdraw the gate to permit fuel to pass to the shovel when the shovel has reached its rearward position.
31. An automatic stoker comprising a horizontally swinging shovel formed with a vertical fuel engaging plate and with a forwardly projecting overhanging part along the upper edge of the vertical fuel engaging plate, and means for operating said shovel.
32. An automatic stoker comprising a pair of shovels, a tension means for said shovels, a shovel actuating cam for alternately setting and releasing said shovels, a vertical ram shaft, a rotary oscillating ram adapted to feed fuel alternately to the shovels, a lever on the ram shaft, and means carried by the shovel actuating cam to engage said lever to oscillate the ram.
33. An automatic stoker comprising a pair of shovels, a tension means for said shovels, a shovel actuating cam for alternately setting and releasing said shovels, a vertical ram shaft, a rotary oscillating ram adapted to feed fuel alternately to the shovels, a two-armed lever on the ram shaft, and means carried by the shovel actuating cam to alternately engage the arms of said lever to oscillate the ram to correspond with the oscillations of the actuating cam.
34. An automatic stoker comprising a pair of horizontally swinging shovels, a tension means for moving said shovels through their fuel throwing movements, a shovel actuating cam pivoted between said shovels and provided with two arms, means carried by each of said arms for alternately setting and releasing the shovels, a horizontally oscillating arm, fuel gates controlling the passage of fuel from the ram compartment to the shovel compartment, means adapted to be engaged by the arms of the shovel actuating cam to raise the gate that controls the fuel supply for the shovel which is in its rearward position.
35. An automatic stoker comprising a pair of horizontal shovels, a tension means for each shovel, means for alternately moving the shovels rearwardly against the tension device, means for releasing one shovel for its fuel throwing movement when the other shovel is in its rearward position, and means to permit the stopping of the operating mechanism only when both shovels are in their rearward positions.
36. An automatic stoker comprising a pair of horizontal shovels, a tension means for each shovel, means for alternately moving the shovels rearwardly against the tension device, means for releasing one shovel for its fuel throwing movement when the other shovel is in its rearward position, and means to prevent the stopping of the operating mechanism when either shovel is in its forward position.
37. An automatic stoker comprising a shovel, an operating mechanism for said shovel, a drive shaft, means connecting the drive shaft to the operating mechanism, a drive member loosely mounted on said shaft, a clutch for connecting said driving member in driving relation with said shaft, a locking disk operating with the driving mechanism, and means whereby said disk will prevent the disconnection of the clutch when the shovel is in its forward movement.
38. An automatic stoker comprising a shovel, an operating mechanism for said shovel, a drive shaft, means connecting the drive shaft to the operating mechanism, a driving member loosely mounted on said shaft, a clutch for connecting said driving member in driving relation with said shaft, a locking disk operating with the driving mechanism, means whereby said disk will prevent the disconnection of the clutch when

the shovel is in its forward movement, and means whereby the locking disk will permit the clutch to be disconnected only when the shovel is in its rearward position.

- 5 39. An automatic stoker comprising a swinging shovel, a tension means for said shovel, means for automatically increasing the tension of said tension means for successive shovel movements, and reducing the 10 length of travel of the shovel as the tension is increased, whereby the shovel will have its greatest movement when the tension is lowest and will have its shortest movement when the tension is greatest.
- 15 40. An automatic stoker comprising a pair of horizontally swinging shovels, means for alternately moving said shovels rearwardly, means for locking them in their rearward position, means for releasing the 20 shovel locking means for one shovel as the other shovel is brought to its rearward locked position, a horizontal oscillating ram for feeding fuel alternately to the shovels, means actuated by the means for moving 25 the shovel to its rearward position for oscillating the ram, and means for moving the shovels through their fuel-throwing movements when the shovel locking means is released.
- 30 41. An automatic stoker comprising a plurality of horizontally movable shovels, means for successively operating said shovels, a fuel feeding means and means for varying the inner limit of successive 35 throws of each shovel.
42. An automatic stoker comprising a horizontally swinging shovel, a horizontally

oscillating fuel feeding ram, a horizontally oscillating shovel actuating means, said means varying the inner limit of movement 40 of the shovel for each succeeding throw of said shovel.

43. An automatic stoker comprising a horizontally swinging shovel, a horizontally oscillating fuel feeding ram, a horizontally 45 oscillating shovel actuating means, and means for varying the inner limit of successive throws of the shovel.

44. An automatic stoker comprising a horizontally swinging shovel, a fuel feeding 50 means, a horizontally oscillating shovel actuating means, means for varying the speed of the shovel in its fuel throwing movements and for varying the inner limit of 55 the shovel movements.

45. An automatic stoker comprising a horizontally swinging shovel, a fuel feeding means, a horizontally oscillating shovel actuating means, means for varying the speed of the shovel in its fuel throwing movements 60 and for varying the inner limit of the shovel movements, the speed of the shovel increasing as the length of movement decreases, the speed of the shovel being decreased as 65 the length of the shovel movement is increased.

In testimony whereof I hereunto affix my signature in the presence of two witnesses this 9th day of September, 1909.

ALFRED COTTON.
